UNITED STATES PATENT OFFICE.

WILLIAM HENRY PARSONS, OF CRISTOBAL, CANAL ZONE.

BOTTLE.

Application filed January 9, 1922. Serial No. 528,048.

To all whom it may concern:

Be it known that I, WILLIAM HENRY PARSONS, a citizen of Manchester, England, residing at Cristobal, Canal Zone, have invented new and useful Improvements in Bottles, of which the following is a specification.

My present invention has reference to a non-refillable bottle.

10 My object is to produce a bottle of this character in which the contents can be readily poured therefrom and in which an attempt at refilling the bottle will be prevented by the seating of a valve in the neck of a 15 bottle.

A further object is to produce a non-refillable bottle having its neck portion provided with a chamber that forms a seat for a spherical valve and which has interior 20 threads above the valve seat that are normally engaged by threads on a plug member, the said plug having grooves between the threads thereof to provide passages which communicate with the valve seat, the 25 head of the plug being of a size approximately equalling the inner cross sectional diameter of the neck is notched, the said notches being arranged out of alignment with the grooves in the plug. These notches 30 in addition to providing outlet passages for the fluid serve as a means whereby the plug may be engaged by a particular and peculiarly shaped wrench so that the plug can be removed should it be desired to again re- 35 fill the bottle, or the plug may be properly positioned after the bottle is filled, the said plug being normally covered by the ordinary cork for the bottle.

The drawing, which accompanies and 40 which forms part of this specification, illustrates a satisfactory embodiment of the improvement reduced to practice, and wherein:

Figure 1 is an approximately central vertical longitudinal sectional view through a 45 non-refillable bottle in accordance with this invention.

Figure 2 is a sectional view on the line 2-2 of Figure 1.

50 Figure 3 is a sectional view on the line 3-3 of Figure 1.

Figure 4 is a sectional view on the line 4-4 of Figure 1.

Figure 5 is a side elevation of the plug.

Figure 6 is a similar view of the wrench 55 which is employed in seating the plug.

The body 1 of the bottle is of the ordinary construction, as is the neck 2, for the major portion of its length. The neck, however, at its juncture with the body 1 is bulged outwardly providing therein a globular chamber 3 whose lower walls are rounded, as at 4 to their juncture with the body proper. The chamber 3 provides a cage for a ball valve 5. The valve is preferably in the nature of 60 a glass sphere, but may be constructed of other weighted and non-corrosive material. The spherical valve 5 when received on the rounded wall 4 effectively closes the passage 65 between the bottle and the neck thereof, and the rounded inner walls of the cage 3 will direct the said sphere to its seat.

Above the portion 3, the neck is thickened to provide the same with interior threads 6, and these threads are engaged by exterior 75 threads 7 on a plug 8. The threads 7, at predetermined intervals are mutilated by being grooved longitudinally of the plug, as at 9, and the portions 9 serve as passages for the 80 outflowing liquid. The plug has its outer end provided with a head 10, and the said head is of a cross sectional diameter only slightly less than the area of the portion of the neck in which it is seated. The head 10 has peripheral notches 11, the said notches 85 being arranged out of alignment with the grooves 9. The neck is normally closed by an ordinary cork or stopper 12.

In arranging the stopper in the neck, I employ a wrench, which is indicated by the 90 numeral 13. This wrench has its shank 14 of a length sufficient to permit of its head 15 being received in the neck of the bottle to engage with the head of the plug and its handle portion 17 being arranged exteriorly 95 of the bottle to permit of the free operation of the wrench. The head 15 is provided with depending prongs 18, corresponding in number with the notches 11 in the head 10 of the plug. It will be apparent that by 100 turning the wrench, the plug will be likewise turned and screwed home in the threaded portion of the neck of the bottle. When it is desired that the bottle be refilled by the owner thereof the plug is screwed in 105 the neck of the bottle without the application of an adhesive to the threaded portion thereof, but when it is desirable that the

plug remain permanently fixed in the bottle neck, the threaded portion thereof is treated with a cement or similar adhesive agent.

The inner end of the plug is disposed only 5 a slight distance above the spherical valve 5, and limits the movement of the valve in its cage 3. The valve, when the bottle is tilted will travel on the rounded wall of its cage to unseated position, permitting the liquid 10 to flow out of the bottle neck, but when the bottle is retained at only a slight inclination the valve will be guided by the rounded or concaved wall of its cage to seated position. The particular arrangement of the notches 15 11 in the head 10 of the plug with respect to the grooves 9 in the body of the plug prevent the insertion of a wire or other implement for holding the valve unseated, and it is thought that the foregoing description, 20 when taken in connection with the drawings

will fully set forth the simplicity and advantages of the improvement.

Having described the invention, I claim:—

A bottle having its neck formed with a spherical compartment at its juncture with 25 the body of the bottle and the walls between the said compartment and the body being rounded, a spherical valve in the compartment normally seated on the rounded lower wall thereof, said neck having interior 30 threads above the compartment, a plug having exterior threads screwed in the neck, said plug having its threaded portion grooved and its outer end headed, and the said head having peripheral notches disposed out of alignment with the grooves in the plug, all as and for the purpose set forth. 35

In testimony whereof I affix my signature.

WILLIAM HENRY PARSONS.
